UNITED STATES PATENT OFFICE.

IRA C. HART, OF BUEHL, IDAHO.

AUTOMOBILE MOTOR-HOOD FASTENER.

Application filed June 14, 1920. Serial No. 388,793.

To all whom it may concern:

Be it known that I, IRA C. HART, a citizen of the United States, residing at Buhl, in the county of Twin Falls and State of Idaho, 5 have invented a new and useful Automobile Motor-Hood Fastener, of which the following is a specification.

My invention relates to improvements in motor-hood fasteners and relates to means 10 to automatically lock the motor-hood of an automobile in a seated position.

One object of the invention is to provide a means for locking a motor-hood which is concealed by the hood when the hood is 15 closed.

A further object of the invention is to provide a means to yieldingly maintain a motor-hood in a seated position and simultaneously yieldingly maintain the hood against its seat. 20

With these and other objects in view reference is now had to the accompanying drawings in which all illustrations are of the fastener placed at the rear left hand corner of the motor, and in which

25 Fig. 1 is a rear elevation of the fastener showing hood in the closed position;

Fig. 1^a is a front elevation of a handle;

Fig. 2 is a front elevation of the fastener showing the hood disengaged from the latch 30 and partly open, and the latch in a receiving position;

Fig. 3 is a side elevation of the fastener;

Fig. 3^a is a partial sectional elevation of the yielding means and housing;

35 Fig. 3^b is a side elevation of the latch;

Fig. 3^c is a side elevation of a shouldered bolt;

Fig. 3^d is a front elevation of a bearing having a notched or grooved face; and

40 Fig. 4 is a plan view of the device.

Having reference to the drawings like numerals and characters refer to like parts throughout the several views and the numeral 1 refers to a standard provided with 45 a suitable foot 19 and terminating at its upper end in a bearing to receive a bolt 5. The bearing is faced at *a* and the face is provided with grooves *b* and *c* respectively which register with a raised portion *d* in the bearing 50 end *e* of the barrel 2 which in turn is rotatably mounted on the bolt 5.

The barrel is cylindrical in form and has an eye 8 rigidly attached to its lower extremity and depends from the bolt 5 so that it 55 may oscillate from above within the range permitted by the raised portion mentioned

and the grooves in the face of the bearing into which the raised portion seats when pressed therein by the spring *f*.

A hollow cylinder 3, also provided with 60 an eye *g*, is slidably mounted in the barrel and the two enclose a spring 20 which acts normally to press the two apart.

A cam shaped latch 4 is movably attached in the eye *g* by means of the bolt 7 and is 65 also movably attached to the eye 8 by means of the link 6 in a manner to present the open side of the latch upward when the barrel is oscillated into the receiving position shown in Fig. 2.

Attached to the motor hood 15 is a brace 16 which carries a cross bar *h* suitably positioned to receive the latch when nearing the closed position and, as the latch oscillates 70 backward, to register with the motor-hood when it is closed, as shown in Fig. 1.

The cross bar extends from and is supported by the braces 14 and 16 and terminates in a bearing at its outer end upon which is rotatably mounted a roller 11 so positioned to bear against the hood seat 12 and thus form a guide to keep the cross bar in registerable position with the latch 4. The rod 10 connects the cross bar and the bearing and maintains them the proper distance 80 apart.

In use the standard is suitably attached to the automobile so that the latch, when in the receiving position, projects outward in a position to receive the cross bar upon its descent. As the cross bar descends to the closing position it is engaged by the latch which is now depressed with the descending cross bar, and which pressing on the latch rotates it on the bolt 7 until the hook *j* in turn registers against the cross bar. The latch now oscillates through the barrel backward and draws the motor-hood against the car as the roller passes the point *k* of the hood seat 12. The latch has now passed the center, beneath the bolt 5, and the tension of the spring 20 maintains the latch in this position and at the same time holds the motor-hood substantially against its seat. 90

A handle 18 is suitably attached to the 105 outside of the motor-hood 15 by means of the brace 17.

Having thus described my invention, I claim—

In an automobile motor-hood fastener, 110 the combination of a standard, terminating in its upper end in a bearing having a

grooved face, a depending barrel rotatably mounted in said bearing and provided with raised portions to register with the grooves of said face, means yieldingly maintaining said raised portion in register with one of said grooves, and engageable with the other of said grooves when said barrel is oscillated, an eye attached to the lower extremity of said barrel, a cylinder slidably mounted in

said barrel, a yielding means enclosed in 10 said barrel and said cylinder to normally press them apart, an eye attached to the lower end of said cylinder, a cam shaped latch movably attached to both of said eyes, and a cross bar attached to said motor-hood 15 and positioned to register with said latch when the motor hood is closed.

IRA C. HART.
